UNITED STATES PATENT OFFICE.

FRANCIS B. ALLDREDGE, OF DES MOINES, IOWA.

BAILER STRUCTURE.

1,421,363.

Specification of Letters Patent. Patented July 4, 1922.

Application filed August 10, 1920. Serial No. 402,612.

To all whom it may concern:

Be it known that I, FRANCIS B. ALLDREDGE, a citizen of the United States, and a resident of Des Moines, in the county of Polk and State of Iowa, have invented a certain new and useful Bailer Structure, of which the following is a specification.

The object of my invention is to provide a bailer structure of simple, durable and inexpensive construction, especially adapted for use in oil and gas wells.

Heretofore in the use of bailers in taking the water from oil and gas wells, an embarrassing difficulty has frequently arisen where the bailer has broken loose from the rope to which it was connected. In such a case, there was no means for removing the bailer, and it has been necessary simply to drill through it, which causes delay and sometimes the loss of a well and always the loss of the bailer.

The bailer heretofore has ordinarily consisted of a long can having a valve at the bottom, and with an ordinary wire or metal bail forming a sort of a handle at the top of the can. When the bailer sometimes becomes stuck the jerk of the engine on the rope will break the bail loose from the bailer can.

It is my purpose to provide a bailer structure where the loss arising from breaking the bailer can from the bail will not occur, and to provide a bailer structure, having a member which can be operated for imparting a sharp blow to the bailer for releasing it in case it should get stuck in the hole.

With these and other objects in view, my invention consists in the construction, arrangement and combination of the various parts of my device, whereby the objects contemplated are attained as hereinafter more fully set forth, pointed out in my claim, and illustrated in the accompanying drawings, in which:

Figure 1 shows a vertical, sectional view through the upper portion of a bailer structure, embodying my invention.

Figure 2 shows a side elevation of the same; and

Figure 3 shows a detailed sectional view of the rope holder, before the rope has been fully installed therein and secured thereto.

In the accompanying drawings, I have used the reference numeral 10 to indicate generally the bailer receptacle, comprising a long can. These cans ordinarily have a

valve in the bottom, which forms no part of my invention and is not here shown.

At the upper part of the bailer can 10 is a contracted neck 11, to which is secured the expanded lower end 12 of a swivel socket 13. Any suitable means may be used for connecting the swivel socket with the upper end of the bailer.

The upper end of the swivel socket is contracted as at 14 and just below the lower end of the contracted portion 14 is a semi-spherical shoulder 15.

It will be understood that in the lower portion of the swivel socket 13 is a vertically, elongated opening or passage 16, which communicates with a restricted passage 17 in the reduced portion 14 at the upper end of said socket.

For use with the device just described, I have provided a rope lift, comprising a tubular member 18, having an opening 19, extending through it from end to end. At the lower end of the tubular member 18 is an enlarged portion 20 having an enlarged opening 21, communicating with the opening or passage 19. Screwed onto the upper end of the rope holder 18 is a nut 22. A wire rope 23 is extended through the opening 19, and its ends are frayed as at 24, and the rope is then securely fastened in the larger opening 21 by means of Babbitt metal or the like, for properly connecting the rope with the rope holder.

In the side wall of the swivel socket is a slot 26, having an enlargement 27 at its lower end.

In the use of my device, the rope is connected with the rope holder. The rope holder is then inserted through the slot 26 until it is entirely received within the swivel socket.

It will, of course, be understood that the enlarged opening 27 is in the lower part of the socket 13 close to the upper end of the bailer.

In the practical use of my improved bailer structure, the bailer is lowered into the well in the ordinary way, and is drawn out when filled with water for removing the water from the well. If the bailer should happen to become stuck in the well, the rope can be lowered slightly and then raised quickly and the shoulder 28 at the upper portion of the enlarged part 20 of the rope holder will strike against the shoulder 15.

It will be understood that the outside of

the shoulder 28 is shaped to conform substantially to the shape of the shoulder 15.

The striking of the shoulders together imparts a sufficient blow to the swivel socket 5 and from thence to the bailer to ordinarily release the bailer, when it has become stuck. This blow can be imparted and given greater or less force, as may be desired.

By allowing the play up and down of the holder in the swivel socket, it is possible to impart a sharp tap or blow to the swivel socket and the bailer, for thus releasing the bailer when it is stuck, and the danger of breaking the rope from the bailer is reduced 15 to a minimum.

The advantage of using a device of this kind whereby the liability of breaking the bailer and leaving it stuck in the well is done away with, is obvious from the foregoing 20 statements.

In the use of the bailer, I am able to effect a great saving of time, and in many instances a very substantial saving in expense.

25 My bailer is of simple and inexpensive construction, and can be used with the ordinary machinery and with the ordinary bailer can, so that in order to install my device in connection with the machinery and 30 parts already in common use, it is only neces-

sary to provide the swivel socket and rope holder in connection with the other parts, which can be done at a relatively small expense.

Some changes may be made in the arrangement and construction of the various parts of my device, without departing from the essential features and purposes of my invention, and it is my intention to cover by my claim, any use of mechanical equivalents 35 or modified forms of structure, which may be reasonably included within its scope.

I claim as my invention:

In a bailer structure, a bailer can, a reduced extended, tubular, swivel socket, having at its upper end a reduced elongated neck, having on its interior a substantially semi-spherical shoulder, said swivel socket, having in its wall, an elongated slot, having a large portion at its lower end, a rope lift 45 comprising a tubular member slidably mounted in said neck, a stopping element detachably mounted on the upper end of said tubular member, and an enlarged hollow portion on the lower end of said tubular member, having an exterior shoulder to contact with said first shoulder, and a flexible member mounted in said rope lift. 50

Des Moines, Iowa, July 30, 1920.

FRANCIS B. ALLDREDGE.
